UNITED STATES PATENT OFFICE.

AUGUSTE F. JACQUEMIN, OF KENNEBUNK, MAINE, ASSIGNOR TO ROGERS FIBRE COMPANY, OF KENNEBUNK, MAINE, A CORPORATION OF MAINE.

DOFFER MECHANISM FOR COUNTER-MOLDING MACHINES.

1,346,030.

Specification of Letters Patent.

Patented July 6, 1920.

Original application filed May 7, 1918, Serial No. 233,031. Divided and this application filed September 17, 1918. Serial No. 254,505.

To all whom it may concern:

Be it known that I, AUGUSTE F. JACQUEMIN, a citizen of the United States, residing at Kennebunk, in the county of York and 5 State of Maine, have invented certain Improvements in Doffer Mechanism for Counter-Molding Machines, of which the following description, in connection with the accompanying drawings, is a specification, 10 like reference characters on the drawings indicating like parts in the several figures.

Counter molding machines of the automatic type usually comprise coöperating center and side molds designed to shape a 15 counter, mechanism for operating said molds to cause them to apply molding pressure to the counter and then to release the counter from the molds, feeding mechanism that delivers the counter blanks one at a 20 time to the molds, and a mechanism that removes the molded counter from the center mold after the molding operation has been completed. This last named mechanism is usually termed in the trade a "doffing mechanism." The present invention is particularly concerned with the mechanism that doffs the counter and it aims to devise a mechanism for performing this operation which will be simple in construction, reliable 25 in operation, which can be economically manufactured, will not be subject to rapid wear or deterioration, and which will generally meet the practical requirements of mechanisms of this type.

The manner in which it is proposed to accomplish these objects will be readily understood from the following description when read in connection with the accompanying drawings and the novel features 30 will be particularly pointed out in the appended claims.

Referring now to the drawings,

Figure 1 is a side elevation of an automatic counter molding machine equipped 45 with a doffing mechanism embodying the present invention, certain parts at the head of the machine being broken away;

Fig. 2 is a side elevation of the doffing mechanism;

50 Fig. 3 is a front elevation of the doffing mechanism;

Fig. 4 is a cross sectional view on the line 4-4, Fig. 3;

Fig. 5 is a front elevation showing certain parts of the molding mechanism; 55

Fig. 6 is a vertical cross sectional view through the mechanism shown in Fig. 5; and

Fig. 7 is a side elevation showing a detail of construction. 60

The invention is herein illustrated as applied to the counter molding machine shown and described in my co-pending application, Serial No. 233,031, filed May 7, 1918, of which application the present case 65 is a division. For a complete understanding of the construction and operation of this machine reference should be made to said application. It is merely necessary for the purposes of the present application to 70 state that the molding apparatus comprises a center mold 2 coöperating with two side molds 3 and 4, Fig. 5, to mold the sides of a counter while a wiper plate 5 moves down over the front faces of the molds and forms 75 a flange C', Figs. 2 and 3, on the counter C. Operating mechanism is provided to relatively move the center and side molds from an open position, in which they are shown in Fig. 5, to a closed or molding position; 80 and this mechanism applies a very heavy pressure to the molds so that they forcibly conform the counter blank to the shape or contour of the molding faces. A feeder, indicated in general at 6, is employed in this 85 machine to present the counter blanks automatically to the molds while they are in their open position. The operating mechanism above referred to then relatively moves the molds to close them upon the counter 90 blank so positioned between them and the wiper plate 5 next descends and crimps the flange while the counter is held by the molds. During this operation the feeder 6 retires to its counter receiving position and 95 after the flange crimping operation has been completed the operating mechanism for the molds again moves them to their open position to permit the removal of the molded counter. The counter at this time 100 rests on the center mold substantially as shown in Figs. 2 and 3 and it is desirable to remove or "doff" the counter from the center mold by moving it in a direction substantially longitudinally of the mold for 105 the purpose of avoiding the spreading apart

of the upper edges of the counter at its forward end during this operation. In order to facilitate this action the center mold 2 is moved forward horizontally out of the plane of the side molds, as indicated in dotted lines in Fig. 6. The doffing mechanism performs its operation while the center mold is in this position.

This doffing mechanism comprises a doffing finger 8 secured fast to a dove-tail plate 9, which is adjustably fastened by bolts 10 in a block 11 that is secured to a slide 12. This slide is mounted in ways formed in a frame 13 that is bolted to the lower end of another slide consisting of a rod 14 which is reciprocated through stationary guides 15 and 16 secured to a bracket 17 that is mounted on the head of the machine frame. In order to reciprocate the rod 14 it has a stud secured thereto which forms a pivotal connection for the lower end of a link 18, the upper end of which is pivoted to the forward end of a lever 20 that is fulcrumed on the bracket 17 at 21. A rod 22 connects the opposite end of the lever 20 through a swiveled head 19, with a lever 23, Fig. 7, carrying a roll that runs in a path 24 formed in a cam 25, Fig. 1, which is secured fast on a shaft 26. This shaft also has fixed thereto a gear 27 driven by a pinion 28 fast on the main shaft 29 of the machine. These connections, therefore, are arranged to operate the doffing in the proper time relationship to the other operations of the machine.

The doffing finger has a movement with the rod 14 and also a movement independently of this rod, the latter movement being produced by a spring mechanism so controlled that the spring is held compressed or tensioned during the first part of the doffing movement and is then released so that it gives the finger a sudden or snap movement. For this purpose the slide 12 is drilled to receive a compression spring 30, Fig. 4, which abuts at one end against the bottom of the hole in this slide and at its opposite end against a spacing block 31 secured between the lower ends of the side members of the frame 13. The slide 12 normally is held in the position in which it is shown in Fig. 3 by a latch 32 pivoted on the frame 13 at 33. A spring 34 encircling a rod, as shown in Fig. 3, acts on the latch to hold it in this position. When the cam 25 acts through the connections with the rod 14 to raise this rod and thus operate through the finger 8 to pull the counter lengthwise off the center mold, the frame 13 and all the parts mounted thereon move bodily with the rod 14 until the upper beveled end of the latch 32 strikes the beveled end of a pivoted stop or trip 35, Fig. 3. The engagement of these two parts trips the latch 32, whereupon the spring 30 immediately expands and throws the slide 12 and the parts carried thereby,

including the doffing finger, upwardly until the slide strikes the upper end of its guideway. The momentum thus imparted to the counter throws it clear off the doffing finger 8 and the counter then strikes a shield or 70 guard 36 that is fastened to the side of the frame 13 and which is curved to deflect the counter laterally away from the molds.

As the rod 14 continues to rise, carrying the frame 13 upwardly with it, it brings the slide 12 into contact with the lower end of a bar 37 which constitutes a stop. This stop, as clearly shown in Figs. 2 and 3, is adjustably secured to a part of the stationary bracket 17 by two bolts 38 which pass 80 through slots formed in the bar and also by a thrust-bolt 39. The contact of the slide 12 with the stop 37 prevents any further upward movement of the slide and, as the bar 14 continues to rise, the slide 12 is depressed against the tension of the spring 30 until the latch 32 is again seated on the upper end of the slide by means of the spring 34. In other words, this operation compresses the spring in readiness for the 90 next doffing movement. The mechanism therefore is of the "load and fire" type, referring to the trade term used in other relationships for somewhat similar mechanisms.

When the doffing descends to doff the next counter the latch 32 again comes into contact with the pivoted stop 35, but at this time it merely rotates the stop in a clockwise direction, as the parts appear in Fig. 3, 100 against the tension of a spring 41 so that the latch is not tripped by its engagement with the stop during the downward stroke of the doffing.

It will now be understood that normally 105 the doffing mechanism is in its raised position where it is out of the path of movements of the other parts of the machine and out of the operator's way, but when the center mold is moved forward into the position indicated in dotted lines in Fig. 6 the doffing is moved downward, and the movements of the two parts preferably are so timed that the doffing finger 8 reaches the lower limit of its stroke just before the center mold reaches the forward limit of its movement. The center mold stops momentarily when its front face comes in contact with the finger 8 and the finger then rises and slides under the flange C' of the counter C, as clearly shown in Figs. 2 and 3. The doffing continues to rise due to the bodily movement of the rod or bar 14, thus causing the finger to lift the counter substantially lengthwise off the center mold. After 120 this doffing movement has been initiated or partially completed the snap action above referred to takes place due to the tripping of the latch 32 by the stop 35. This movement accelerates the motion of the counter, 130

completing the removal of the counter from the center mold and throwing it laterally away from the molds due to its contact with the deflector 36.

- 5 It will be evident to those skilled in this art that the invention is susceptible of embodiment in many forms differing in organization and details of construction from the embodiment herein disclosed without de-
10 parting from the spirit or scope of this invention.

What is claimed as new, is:

1. In a counter molding machine, a counter doffing mechanism comprising a counter engaging device constructed to engage the flange of a molded counter and operating mechanism therefor arranged to give said device a relatively slow movement to initiate the counter doffing action and 15 thereafter to give the device a greatly accelerated movement in the same general direction to complete said operation.

2. In a counter molding machine, a counter doffing mechanism comprising a doffer finger for engaging the flange of a molded counter and mechanism for operating said finger comprising a cam operated device for giving the finger a to and fro movement, and means partaking of said 20 movement but operative to accelerate the doffing movement of the finger.

3. In a counter molding machine, a doffer finger for engaging the flange of a molded counter, a support for said finger, a spring 35 acting through said support to give said finger a doffing movement, means for giving said support and finger a to and fro stroke, and mechanism operative to tension said spring at one part of said stroke and to release said spring at another part of said 40 stroke.

4. In a counter molding machine, a doffer finger for engaging the flange of a molded counter, spring actuated mechanism for operating said finger, means for moving said finger back and forth in a predetermined path, and means operative to tension said mechanism during a certain portion of said movement and to release said mechanism at 45 another part of said movement.

5. In a counter molding machine, the combination with a center mold, coöperating side molds, and operating mechanism for relatively moving said molds, of a doffing mechanism comprising means operative to remove the counter from the center mold in the general direction of the length of the mold and additional means for engaging the counter and guiding it laterally away from 55 said molds.

6. In a counter molding machine, the combination with a center mold, coöperating side molds, and operating mechanism for relatively moving said molds, of doffing mechanism for removing the counter from 65 said center mold comprising means for throwing the counter away from the mold in the general direction of the length of the mold, and means for deflecting the counter laterally away from said molds. 70

7. In a counter molding machine, the combination with a center mold, coöperating side molds, and operating mechanism for relatively moving said molds, of doffing mechanism for removing the counter from 75 said center mold comprising a doffer finger for engaging the flange of the counter, means for operating said finger to throw the counter away from the mold in the general direction of the length of the mold, and a 80 deflector arranged to engage the counter after it leaves said finger to guide it away from said molds.

8. In a counter molding machine, a counter doffing mechanism comprising, in 85 combination, a doffer finger, a slide supporting said finger, a reciprocating support on which said slide is mounted, a spring between said support and said slide tending to give the finger a doffing movement, a latch 90 normally holding the finger against said movement by the spring, means for moving said support in one direction to initiate the doffing operation and for returning the support again to its original position, and 95 means for tripping said latch during said doffing movement of the support to enable the movement of the slide produced by said spring to complete the doffing operation.

9. In a counter molding machine, a 100 counter doffing mechanism comprising, in combination, a doffer finger, a reciprocating support, means for reciprocating said support to effect the doffing operation, a slide supporting said finger and mounted on said 105 support for sliding movement relatively thereto, a spring between said support and said slide tending to give the slide a doffing movement independent of the movement of the support, a latch normally restraining 110 said slide, a stop against which the latch is carried during the doffing movement of said support, said stop being operative to trip the latch to release said slide, and a stationary member engaged by the slide at a subsequent 115 point in the stroke of said support to tension said spring and reset the slide.

In testimony whereof I have signed my name to this specification.

AUGUSTE F. JACQUEMIN.
